Patented May 6, 1919.

UNITED STATES PATENT OFFICE.

CHARLES F. ABERNATHY, OF WEST ASHEVILLE, NORTH CAROLINA.

SURGICAL APPLIANCE.

1,302,751.

Specification of Letters Patent.

Patented May 6, 1919.

Application filed December 4, 1917. Serial No. 205,381.

To all whom it may concern:

Be it known that I, CHARLES F. ABERNATHY, a citizen of the United States, residing at West Asheville, in the county of Buncombe and State of North Carolina, have invented a new and useful Surgical Appliance, of which the following is a specification.

The device forming the subject matter of this application is adapted to be employed for applying tension to a broken leg, and one object of the invention is to provide novel means whereby the sheave across which the leg-pulling cord is stretched, may be held in adjusted positions, vertically, thereby to alter the angle at which the injured leg is disposed with respect to the horizontal.

Another object of the invention is to provide a device of the kind mentioned which may be assembled readily with beds of widely different constructions.

It is within the province of the disclosure to improve generally and to enhance the utility of devices of that type to which the present invention appertains.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings:

Figure 1 shows in elevation, a device constructed in accordance with the present invention, the same being attached to the foot frame of a bedstead;

Fig. 2 is a vertical section taken through the foot frame of the bedstead, the device forming the subject matter of this application being shown, for the most part, in elevation, and parts being broken away;

Fig. 3 is a cross section taken on the line 3—3 of Fig. 1.

In carrying out the present invention, there is provided a body 1 in the form of a plate, made of any desired material and supplied at its upper end with a notch or seat 2, the body being reinforced by a peripheral bead 3 on the forward face of the body 1. Below the seat 2, there is a projecting boss 4 which will be alluded to hereinafter. On the rear face of the body 1, a securing device, such as a hook 5, is located.

Adjacent its upper end and below the boss 4 the body 1 is provided with a main longitudinal slot 6 which extends through the body. Guides 7 are attached to the forward face of the body 1 on opposite sides of the main slot 6, the lower ends of the guides 7 being inclined toward each other to form stops 8. Openings 9 are fashioned in the body 1 on opposite sides of the main slot 6, and in selected pairs of these openings, U bolts 10 and 11 may be mounted, the U bolts 10 and 11 being of different sizes, if desired. Wing nuts 12 are threaded on the forward ends of the U bolts 10 and 11 and coöperate with the forward face of the body 1. Near to its lower end the body is supplied with a longitudinal auxiliary slot 14, in which a holding device, such as a U bolt 15, is mounted for vertical adjustment. The U bolt 15 passes through a plate 16, extending laterally beyond the edges of slot 14 and bearing on the forward face of the body 1 to prevent the U bolt from being drawn through the slot 14. The rearwardly projecting arms of the U bolt 15 pass through a plate 17 spaced from the rear face of the body 1, there being nuts 18 on the arms of the U bolt, the nuts coöperating with the plate 17.

A rider 19 is mounted for vertical adjustment in the guides 7 and bears against the forward face of the body 1 on opposite sides of the main slot 6. The rider 19 includes a tubular forward extension 20 in which a sheave 21 is journaled for rotation, the sheave extending backwardly into the main slot 6. A flexible element 22 is attached to the upper end of the rider 19 and passes across the boss 4 and across the upper end of the body 1, the flexible element being received in the notch or seat 2, to prevent a sidewise movement of the flexible element. The rear end of the flexible element 22 is detachably engaged with the hook or securing device 5. At this point it is to be observed that the boss 4 exercises two functions. First it constitutes a stop, limiting the upward movement of the rider 19, the downward movement thereof being limited by the parts 8; and secondly, the boss 4 serves to thicken the body 1 and to reinforce the body, the forward end of the hook 5 being extended into the boss.

The numeral 23 marks a second flexible element, trained across the sheave 21 on the rider 19, and the rear end 24 of the flexible element being extended through the slot 6 in

the body 1. A hanger 25 is attached by means of a hook 32, or otherwise, to the lower end of the flexible element 23 and carries removable weights 26 supported on the 5 button 27 attached to the lower end of the hanger, the weights constituting means for applying tension to the flexible element 23.

The numeral 28 marks the foot frame of a bed which, of course, may be variously constructed, the frame in the present instance being shown as comprising a top rail 29 and a bottom rail 31. The U bolts 10 engage the top rail 29, and the bottom rail 31 is bound against the body 1 by means of the plate 17 10 and the U bolt 15. It is to be observed that the U bolt 15 may be adjusted vertically in slot 14 so as to coöperate with the rail 31, regardless of the height of the rail. The U bolts 10 may also be adjusted vertically in 15 the openings 9, and the same observation holds true with regard to the U bolt 11, the latter element being adapted to engage bed parts not shown in the particular frame 28 delineated in the drawings. It is of course 20 to be understood that some of the U bolts 15, 10 and 11 may be used, to the exclusion of the others, depending upon the construction of the foot frame of the bed, it being essential merely that some suitable means be 25 provided whereby the body 1 is held securely in a vertical position on the foot frame.

The rider 19 may be raised and lowered and may be held in adjusted positions by engaging the flexible element 22 with the hook 35 5. In this way, the height of the sheave 21 may be regulated and the angle which the leg of the patient assumes with respect to the horizontal may be adjusted.

Having thus described the invention, what 40 is claimed is:

1. A device for applying tension to an injured limb, comprising a plate-like body hav-

ing a restricted slot elongated longitudinally of the body; guides secured to the forward face of the body on opposite sides of the 45 slot; a rider mounted to reciprocate in the guides; a sheave journaled on the rider and received in the slot; a flexible element trained across the sheave and extended through the slot; means for applying tension to the flexible element; and a second flexible element connected at one end to the rider, the flexible element being extended across the upper edge of the body; and means on the rear face of the body for engaging the second flexible ele- 50 55 ment detachably.

2. A device for applying tension to an injured limb, comprising a plate-like body having a restricted slot extended longitudinally of the body; guides secured to the forward 60 face of the body on opposite sides of the slot; a rider mounted to reciprocate in the guides; a sheave journaled on the rider and received in the slot; a flexible element trained across the sheave and extended through the 65 slot; means for applying tension to the flexible element; a boss on the forward face of the body above the guides and constituting a stop for the rider; a holding device on the rear face of the body and extended into the 70 boss; and a second flexible element trained across the upper end of the body and extended across the boss, one end of the second flexible element being detachably engaged with the holding device, the other end of the 75 second flexible element being connected with the rider.

In testimony that I claim the foregoing as my own, I have hereto affixed my signature in the presence of two witnesses.

CHARLES F. ABERNATHY.

Witnesses:

J. M. BROOKSHIRE,
J. J. MACKEY.
